UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WINDING MACHINE.

Application filed December 8, 1922. Serial No. 605,687.

To all whom it may concern:

Be it known that I, ELBRIDGE R. HOLMES, a citizen of the United States, residing at Worcester, in the county of Worcester and 5 State of Massachusetts, have invented a new and useful Winding Machine, of which the following is a specification.

This invention relates to a winding machine of general application but particularly 10 adapted for winding the warp spools used in narrow ware looms. It is desirable that such spools be wound under relatively heavy pressure, which pressure must be relieved or released when a full spool is to be re- 15 moved and replaced.

It is the general object of my invention to provide an improved device for thus applying and releasing the pressure on the spools.

A further object is to provide means for 20 holding the tension devices in operative or inoperative position, as desired.

An important feature of my invention also relates to the provision of an equalizing device, by the use of which tension may be 25 applied to either cylindrical or tapered spools.

Further features of my invention will be hereinafter described and more particularly pointed out in the appended claims.

30 A preferred form of the invention is shown in the drawings, in which

Fig. 1 is a side elevation of my improved winding machine;

Fig. 2 is a rear elevation thereof;

35 Fig. 3 is a plan view of the machine;

Fig. 4 is a detail sectional elevation taken along the line 4—4 in Fig. 1; and

Fig. 5 is a detail sectional elevation, taken along the line 5—5 in Fig. 3.

40 Referring to the drawings, I have shown my improvements applied to a winding machine which is in general of a common type. The machine as shown comprises end frames 10 and 11 held in suitable spaced relation by

45 cross rods 12 and supporting a driving shaft 13 in bearings 14. Tight and loose pulleys 15 and 16 are provided on the driving shaft 13 and a shipper handle 17 and shipper fork 17^a control the position of a driving belt 18 thereon.

The shaft 13 is connected by a pinion 18 and gear 19 to a winding shaft 20 on which

a winding drum 21 is mounted. The yarn spools 22 rest upon the drum 21 and are rotated thereby. These spools may be either 55 of the usual cylindrical shape or of the slightly tapered shape shown in the drawings. A hand wheel 23 on the shaft 20 is provided for occasional manual rotation of the drum 21. A second shipper handle 24 60 may also be provided at the front of the machine, the two handles being connected so that the machine may be started or stopped from either the front or the rear.

The parts thus far described are in general 65 of the usual construction and in themselves form no part of my invention which relates particularly to the devices for applying pressure to the spools 22. The spools 22 have projecting bearings or gudgeons at 70 their ends adapted to be received in bearing recesses in the under side of tension arms 25, these recesses being open at their undersides. The arms 25 are pivoted at the ends of an equalizing lever 26 which in turn is 75 pivoted on a stud 27 fixed in a collar 28 mounted on one of the cross rods 12 of the machine frame. Stop arms 29 are also adjustably secured to the cross rod 12 and limit angular equalizing movement of the 80 lever 26.

A tension device is provided at each side 85 of the machine for applying heavy downward pressure to each arm 25. Each of these devices comprises an arm 30 (Fig. 1), connected at its outer end by a pin 32 to the lower end of a weight rod 33 upon which any desired number of removable weights 34 may be placed. The upper end of each rod 33 is pivotally connected by a cross pin 90 35 (Fig. 4) to a supporting member 36.

A grooved roll 37 is mounted on a stud 38 fixed in the member 36 and engages the upper edge of the corresponding tension arm 25, thus transferring the downward 95 pull of the weights 34 to the arms 25 which, in turn, press downward upon the gudgeons or bearings of the spool 22 which is in the machine.

Each arm 25 is provided with two openings 39 and 40 and the member 36 is provided with a locking pin 41 mounted to slide transversely and to enter one or the other of the openings 39 and 40. The member 36

may thus be locked in the operative position shown in full lines in Fig. 1 or in the inoperative position shown in dotted lines in said figure.

5 A spring actuated latch 42 is provided for manually withdrawing the locking pin 41 and for yieldingly advancing the pin to locking position. Projections 43 are provided on the arms 25 to limit movement of 10 the members 36 in both directions, and handles 44 on the ends of the arms 25 permit the operator to raise the arms to release the spools when desired.

Having described the details of construction of my improved machine, I will now point out its advantages in operation:

15 The usual running position of the parts is shown in full lines in Fig. 1, with the members 36 locked in the forward position. With the parts thus disposed, the 20 weights 34 exert their weight upon the bearings of the spool 22, thus causing the spool to be wound under heavy pressure. When it is desired to remove and replace a full 25 spool, the locking pins 41 are withdrawn by means of the latches 42 and the members 36 are then pushed backward on the arms 25 to the position shown in dotted lines in Fig. 1.

30 In this position the weights 34 are supported directly over the pivots of the arms 25, and the arms may be readily lifted by the handles 44 without raising the heavy 35 weights 34. The labor involved in removing and replacing a full spool is thus greatly reduced, as only the light arms 25 need be raised.

The equalizing lever 26 permits the 40 machine to be used with either tapered or cylindrical spools and equalizes the pressure upon the two ends of the spool.

Having thus described my invention and the operation and advantages thereof, I do not wish to be limited to the details herein 45 disclosed otherwise than as set forth in the claims, but what I claim is:

50 1. In a winding machine, a winding drum, a spool supported in rolling contact with said drum, pivoted bearing members for said spool, and means to apply pressure to said bearing members, said pressure applying means being movable to transfer the pressure to points adjacent the pivoted support of said members and to thereby render 55 said pressure applying means inoperative.

55 2. In a winding machine, a winding drum, a spool supported in rolling contact with said drum, pressure arms having bearings for said spool, and means to apply pressure

to each arm, said pressure means being movable to operative and inoperative positions on said pressure arms.

3. In a winding machine, a winding drum, a spool supported in rolling contact with said drum, arms having bearings for said spool, means to apply pressure to each arm, said pressure means being movable to operative and inoperative positions on said arms, and locking devices for said pressure means.

4. In a winding machine, a winding drum, a spool supported in rolling contact with said drum, arms having supports on said machine and having bearings for said spool, weighted rods supported on said arms, and means permitting shifting of said rods on said arms to selected positions adjacent to or removed from the points of support of said arms.

5. In a winding machine, a winding drum, a spool supported in rolling contact with said drum, arms having supports on said machine and having bearings for said spool, weighted rods supported on said arms, means permitting shifting of said rods on said arms to selected positions adjacent to or removed from the points of support of said arms, and means to hold said rods in said selected positions.

6. In a winding machine, a winding drum, a spool supported in rolling contact with said drum, pivoted pressure arms having bearings for said spool, a pair of weighted members, a supporting roll for each member mounted for movement along one of said pressure arms, and means to secure each of said members in selected positions on said arms adjacent to or removed from the pivots of said pressure arms.

7. In a winding machine, a winding drum, a spool supported in rolling contact with said drum, pressure arms having bearings for said spool, a pair of weighted members, a guide roll on each member supported on one of said pressure arms, stops for said rolls on said arms, and locking devices to position said members on said arms, said members being movable on said arms to operative or inoperative position thereon.

8. In a winding machine, a winding drum, a spool supported in rolling contact with said drum, arms having bearings for said spool, an equalizing lever for said arms, and separate means to apply pressure to each arm.

In testimony whereof I have hereunto affixed my signature.

ELBRIDGE R. HOLMES.
